UNITED STATES PATENT OFFICE

FREDERIC D. COURTENAY, OF SHORT HILLS, NEW JERSEY, ASSIGNOR TO EMBOSOGRAF CORPORATION OF AMERICA, OF NEW YORK, N. Y., A CORPORATION OF NEW YORK

DESIGN FOR A SIGN DISPLAY STAND

Application filed November 22, 1930. Serial No. 37,759. Term of patent 7 years.

To all whom it may concern:

Be it known that I, FREDERIC D. COURTENAY, a citizen of the United States, and resident of Short Hills, in the county of Essex and State of New Jersey, have invented a new, original, and ornamental Design for Sign Display Stands, of which the following is a specification, reference being had to the accompanying drawings, forming a part hereof.

In the drawings, Fig. 1 is a perspective

view of the stand showing my new design;

Fig. 2 a side view of the upper portion of the stand upon a larger scale; and

Fig. 3 a face view of the upper portion of the stand.

I claim:

The ornamental design for a sign display stand substantially as shown.

FREDERIC D. COURTENAY.
